Application February 27, 1948, Serial No. 11,623

13 Claims. (Cl. 250—141)

1

My invention relates to cathode ray tubes and in particular to a means to suppress arc-overs between electrodes maintained at high differences of potential during tube operation.

Cathode ray tubes, used in one form of projection type television receivers, utilize an electron gun structure having a second anode or accelerating electrode maintained at close to 27,000 volts positive relative to the reference or cathode potential during tube operation. The second anode electrode in these tubes may comprise a conductive internal bulb coating, with which the possibility of breakdown or arc-over to lower voltage electrodes exists. Breakdown or arc-over within the tube is a problem on higher voltage tubes particularly in the region between the second anode coating and the end of a first anode electrode. A high gradient appears in this region and internal arc-overs may occur. Also, a high gradient appears near the edge of the second anode coating or at the edge of the grounded external neck coating which serves as a shield between the deflecting yoke and the tube if it does not overlap the internal coating. This non-uniform gradient tends to produce failure near the second anode coating edge. Edge-break-down failure such as this is well known from electrical break-down tests on glass and other insulators.

It has been observed that internal arcs through the vacuum space do not usually produce permanent damage providing the peak arc current is limited. Under these conditions the arc-over is momentary in most cases. However, it is not usually possible to limit the current enough without resulting in poor voltage regulation of the second anode supply so that the arc-overs are sustained and often overheat internal parts, causing excessive gas and fracture of the glass envelope.

It is therefore an object of my invention to provide means for improving the operation of cathode ray tubes.

It is a further object of my invention to provide means for preventing electrical breakdown between elements of a cathode ray tube.

It is another object of my invention to provide means for suppressing arc-overs between elements of a cathode ray tube.

It is a further object of my invention to provide means for suppressing arc-overs between electrodes of a cathode ray tube maintained at a high difference of potential.

It is a further object of my invention to provide means for suppressing arc-overs between a

2

conductive wall coating and adjacent tube elements.

It is also an object of my invention to provide means for suppressing arc-overs between a conductive wall coating of a cathode ray tube and adjacent electrodes.

It is a further object of my invention to provide means for suppressing corona discharge between an internal conductive coating of a cathode ray tube and an adjacent external tube element.

The novel features which I believe to be characteristic of my invention are set forth with particularity in the appended claims, but the invention itself will best be understood by reference to the following description taken in connection with the accompanying drawing, in which:

Figure 1 is a cross sectional view of a cathode ray tube incorporating my invention;

Figure 2 is an enlarged partial view of a conventional cathode ray tube similar to that of Figure 1;

Figure 3 is a sectional view of a cathode ray tube incorporating a modification of my invention; and

Figure 4 is a cathode ray tube incorporating another modification of my invention.

Referring to Figure 1, there is disclosed a cathode ray tube of the projection type for reproducing television images. The illustrated tube consists of a conventional glass or similar vitreous elongated envelope 10 having a cone or bulb shaped end 11 and an elongated neck portion 18. Closing the bulb end of the envelope is a glass face plate 12, on the inner surface of which is deposited a phosphor screen 14 covered by a thin aluminum metal screen 16. Within the neck portion 18 of the receiving tube is provided an electron gun structure for generating and focusing a beam of electrons upon the phosphor screen 14.

This electron gun structure comprises a tubular support 20 mounted coaxially within the envelope portion 18. The support 20 encloses an indirectly heated, oxide coated cathode (not shown) which serves as the source for the beam electrons.

The control grid (also not shown) is in the form of an apertured plate spaced a few mils from the activated cathode surface and closing the end of the tubular support 20 facing the fluorescent screen. Coaxially spaced from the control grid is a shield electrode 22 comprising a short cylindrical tube supporting a transverse apertured disc (not shown). The shield electrode 22 is normally operated in one type of tube

at a positive potential relative to cathode potential of approximately 200 volts. Electrode 22

serves to prevent interaction between the fields of the control grid and the focusing fields of the anode electrodes described below.

A tubular first anode electrode 24 is axially spaced as is shown from the second grid 22. The first anode electrode is normally operated in the mentioned type of tube at around 4800 volts. The lens formed between the shield electrode 22 and the first anode 24 aids in the focusing of the electrons passing through the aperture of the screen electrode 22. A second lens is formed between the first anode electrode 24 and a second anode electrode, which comprises conductive graphite coating 26 on the inner surface of the envelope neck 18. The second anode coating 26 extends as is shown into the bulb portion 11 and makes contact with the aluminum screen 13. The lens between the first anode electrode 24 and the second anode electrode 26 provides a final focus to the electrons passing through the tubular electrode 24 and forms them into a beam 27 focused upon the fluorescent screen 14. The second anode electrode 26 may be operated in the one type of the tube, mentioned above, at around 27,000 volts. The appropriate potentials are maintained on the several electrodes described above by leads sealed through the closed end of the envelope neck portion 18. These leads are in turn connected to base pins 30 fixed into the tube base 28. The second anode 26 is connected to the external circuit (not shown) through a lead conductor 32. The lead 32 may comprise a metal cavity cup sealed through the wall of the envelope bulb 11 and in contact with the graphite conductive coating 26 of the second anode.

The electron beam 27 is caused to scan over the surface of the fluorescent screen 14 by either well known electrostatic or electromagnetic deflection movements. Figure 1 shows electromagnetic scanning means at 34 which is a neck yoke including coils that produce fields at right angles to each other and to the axis of the tube. These coils would be connected to the usual saw-tooth or other variable current sources of line and frame frequency (not shown).

In tubes, of the type described above, the second anode electrode 26 is operated at a positive potential up to 30,000 volts. Under such conditions, field emission between the first and second anode electrodes, becomes a serious problem. Besides reducing contrast by random illumination of the screen, fairly well focused beams of field emitted electrons impinging on the neck 18 adjacent the first anode thimble 25 cause localized heating which result in punctured and cracked necks. As illustrated in Figure 2, in a conventional tube there is a high field gradient between the first anode electrode 24 and the second anode coating 26 on the adjacent neck portion. Internal arc-overs usually occur in this region due to several things. A concentration of field emission will produce a heating of the glass tube wall to release occluded gas therefrom which will support an arc-over. Also, any roughness of, or projections from the conductive graphite coating 26 will form paths of less resistance for the field emission. The field emission will seek out such points and will concentrate at these points to form a hot spot.

There is also another field concentration, disclosed in Figure 2, between the end of the conductive coating 26 and both the thimble 25 and the grounded conductive coating 36 on the outside surface of the tube bulb. Since both the grounded coating 36 and the first anode electrode

24 overlap the end of the conductive coating 26, this field concentration or "end-effect" not only encourages arc-over between the electrode 24 and the high potential coating 26 but also tends to cause puncture of the tube neck. This results from the fact that the field concentration produces a non-uniform potential gradient in the glass wall, thus increasing unit stress. This increased gradient also acts to produce field emission at the end of the coating and field emission tends to heat the glass walls of the tube, and in accordance with thermal breakdown theory which is well supported by experiment with glass, this leads to electrical puncture or breakage of the glass. I have observed that arc-overs between the first and second anode electrodes do not usually produce permanent damage if the peak current is limited. In fact when the current is limited, the arc-over is only momentary in most cases. However, it is not usually possible to limit the current of the arc-over enough without causing poor voltage regulation in the supply circuits of the anode electrodes.

It is often possible to burn out or remove field emission by a process known as "spot knocking." The electrodes are subjected to about twice the normal operating voltage in series with a limiting resistor. Under favorable conditions enough current can be allowed to flow, during arc-over, to fuse or melt off the sharp points or irregularities causing field emission. In practice this is not always successful, and the current is likely to be raised high enough to produce a destructive arc. This process not only requires time and special equipment for tube manufacture but also requires skill and good judgement to avoid an excessive number of ruined tubes. In addition it has been observed that the tubes sometimes contain a small amount of fine loose particles 40 which may move and settle at a point of high gradient after the tube is handled. This may then result in the recurrence of field emission at operating voltages. Whereas "spot knocking" was required on nearly all of the tubes of old construction and a number of them were damaged, my invention practically avoids the need for it and, in the few cases where it is needed, does not result in tube failure.

As a solution of the problems outlined above, I have provided, as shown in Figures 1 and 3, a means for suppressing internal arc-overs within the tube to avoid damage incident to such electrical breakdown. My novel solution is to provide a semi-conducting coating 38 in the region of the first anode electrode 24. The conductive coating 26 is stopped short of the first anode electrode thimble 25 and the second anode is continued as a semi-conducting coating 38 to a point on the neck wall overlapping the first anode thimble 25. This strip of coating material 38 is still part of the second anode electrode and, as will be pointed out, provides a focusing and accelerating field for the electron beam 27. The semi-conductive coating material 38 is preferably a mixture of aluminum oxide suspended in a sodium silicate solution. This material is applied wet to the inside of the neck wall and then baked until the water is driven off and the coating becomes a hard adherent substantially gas free layer. The aluminum oxide together with the sodium silicate provides a high resistance or a very low conductivity layer. The coating material should have a desirable range of resistivity in the order of between 10^7 and 10^9 ohms. The resistance should be such that the

current tolerated must not be more than approximately 50 micro-amps flowing through the material. That is, the conductivity of the coating material 38 must be high enough to take care of stray field emission and leakage currents between the two electrodes 24 and 26 so that these currents may be carried off and allow the area to return to an equilibrium potential within about one second.

When high voltage potential is applied to the anode coating 26 during tube operation, the conductivity of the coating 38 is sufficient to permit at least the upper part of the coating 38 to assume the high potential. In case field emission is present, or due to an increase of voltage an arc is established between the first anode electrode and the second anode coating 38, the potential around the hot spot, which tends to develop on coating 38, will drop immediately before the current in the arc can build up and produce damaging effects. With the drop in voltage, ionization ceases and the arc stops. The drop in potential through the coating 38, around any point of concentration of field emission or arc from the first anode, is due to the low conductivity of coating 38, which thus produces a large voltage drop even with a very small current. The use of the coating 38 prevents any concentration of heating, since the drop in potential at the point of concentration will cause the discharge to spread out and over-heating of the glass parts of the tube will be prevented. The electrical path that an arc discharge would normally take in this region of tube 10, is along a low resistance arc between the first anode electrode 24 and the second anode coating 26, then along the high conductivity path of the second anode coating 26 to the second anode lead 32. The presence, however, of coating 38 provides a high resistance in series with the arc path and the high conductivity path of the coating 26. Thus, one function of such a high resistance portion 38 of the second anode electrode is to quench and remove any arc discharge established between the first and second anode electrodes 24 and 26 respectively. It is obvious that the high conductivity portion of coating 26 should be sufficiently spaced from the first anode electrode 24 to prevent direct arcing between the first anode and the conductive coating 26.

The use of the low conductivity coating 38 also reduces the danger of an arc-over between the grounded coating 36 and the second anode electrode 26, which would result in destructive puncturing of the glass neck wall as described above. In tubes of the type described relative to my invention, there is often provided a bulb spacer 23 (Figures 1 and 2) mounted on the first anode tube 24 and provided with fingers 29 for resiliently positioning the first anode tube 24 along the axis of the neck portion 18. The spacer 23, usually of a metallic material, will be at first anode potential during tube operation. Due to the use of high second anode potentials relative to that of the first anode 24, there will be current leakage across the glass surface of the neck 18 between the spring fingers 29 and the second anode coating 26 (Figure 2). The use of the low conductivity coating 38 (Figure 1) results in a field gradient being established in the low conductivity coating 38 by this surface leakage from the spring fingers 29. This potential gradient in the coating 38 between the second anode coating 26 and the edge of coating 38 facing the fingers 29 will eliminate any dangerous

concentration of field between the end of the second anode coating 26 and the grounded coating 36, (Figures 1 and 2).

It is also characteristic of the electrical breakdown of glass according to the thermal breakdown theory, that leakage current flows and tends to concentrate in a narrow path due to heating of the glass which has a negative temperature coefficient of resistance. The low conductivity coating 38 acts to suppress this current concentration in the region most susceptible to puncture.

An alternative application of my invention is disclosed in Figure 3 in which a low conductivity coating 42 is placed between two portions 40 and 26 of the second anode electrode. The low conductivity coating 42 is applied preferably in the portion of the tube where the neck begins to flare and form the bulb portion 11. This arrangement also provides a high resistance path 42 in the arc discharge path between the first anode electrode 24 and the second anode contact lead 32 similar to that as described above for Figure 1. The low conductivity coating 42 will prevent destructive arc-overs since any arc-over which will develop between electrode 24 and the second anode coating portion 40 will reduce the potential of portion 40 so that the voltage and current are decreased and the arc suppressed. The conductivity of the coating strip 42 is similar to that of coating 38 in the modification of Figure 1 and is such as to permit the second anode portion 40 to regain its high potential within a very short time after any arc-over.

Another advantage of positioning the semi-conductive coating 42 at the beginning of the neck is that in this position, coating 42 acts to reduce any edge effect between the forward edge of the grounded outside neck coating 36 and the high potential coating 26 on the inner surface of the tube. Thus, glass puncture due to corona between the yoke 34 or coating 36 and the second anode coating 26 is prevented.

It is not necessary to use an internal neck coating on the bulb surface to provide a high resistance in the arc-over path between the first and second anode electrodes. In Figure 4, the second anode electrode is deposited on the inside wall of the tube in two portions; one portion being a conductive layer, 26, on the inner surface of the bulb 11 and a second portion, 40, deposited on the neck 18 of the tube and overlapping the first anode electrode 24. The anode portions 26 and 40 are spaced along the inside surface of the tube so that there is a space 44 of insulating glass between them. The second anode coating portion 26 is connected to its source of high potential through the second anode contact lead 32 and a conductive lead 46. Also the second anode portion 40 is connected to the same source of high potential by a conductor 50 passing through the glass wall of the neck. However, between the two anode portions 26 and 40 is placed a high resistance element 48. The resistor 48 may have a value of between 10,000 to 10,000,000 ohms. The resistance 48 functions in a manner similar to the conductive coatings 32 and 48 described in the modifications of Figures 1 and 3, respectively. If the conditions are such, during the operation of the tube of Figure 4, to establish a concentration of the field emission and support to an arc-over between the first anode electrode 24 and the second anode portion 40, the presence of the resistor 48 in the circuit of the second anode portion 40 will result in a drop in the potential of

portion 40 below that at which the arc can be sustained.

It has been mentioned above that the coating material 38 and 40 may consist of a mixture of aluminum oxide powder in a suspension of sodium silicate. However, it is possible to obtain equally good results with other powders of insulating or semi-insulating material. For example, finely divided ferric oxide or chromic oxide may be substituted for the aluminum oxide. Any finely divided metal having surface layers of insulating or semi-insulating oxides, for example, iron, nickel and copper may be substituted for the metal oxide of the semi-conductive coatings 38 and 42. Also any other high resistance coating suitable for use in a vacuum tube may be used.

In using a ferric oxide mixture, good results have been obtained by dissolving 100 to 125 grams of sodium silicate in 260 to 500 cc. of distilled water. The solution may be heated and 500 grams of finely powdered ferric oxide (Fe_2O_3) may be added slowly and with constant stirring. The proportions of the constituents can be varied considerably without impairing the effectiveness of the coating as long as the resistivity of the coating is approximately within the limits described above. This coating mixture may be applied to the inner surface of the glass envelope 19 in any convenient way as by the use of a brush, spray, etc., and in as thin a layer as will produce the desired conductivity.

While certain specific embodiments have been illustrated and described, it will be understood that various changes and modifications may be made therein without departing from the spirit and scope of the invention.

What I claim as new is:

1. A cathode ray tube comprising an envelope, a first anode electrode mounted within said envelope and adapted to be maintained at an operational potential, said first anode electrode spaced from the wall of said envelope, a second anode electrode including a conductive coating on the inner surface of said wall, lead means connected to one portion of said second anode coating for connecting said second anode to a source of higher potential relative to that maintained on said first anode electrode during tube operation, and means of high electrical resistivity electrically connected to another portion of said second anode coating and between said first anode electrode and said one portion of said second anode coating.

2. An electron discharge device comprising an evacuated envelope, a first electrode mounted within said envelope and adapted to be maintained at an operational potential, said electrode spaced from a portion of the wall of said envelope, a second electrode including a conductive coating on the inner surface of said wall portion, lead means sealed through said wall portion for connecting said conductive coating to a source of higher potential relative to that maintained on said first electrode during tube operation, said conductive coating including a semiconductive coating on the wall of said envelope and more adjacent said first electrode than said lead means, said semiconductive coating having high electrical resistance and in electrical contact with said second electrode to suppress electrical discharges between said first and second electrodes.

3. A cathode ray tube comprising an envelope, a first anode electrode mounted within said envelope and adapted to be maintained at an operational potential, said anode electrode spaced

5 from the wall of said envelope, a second anode electrode including a conductive coating on the inner surface of said wall, lead means sealed through said wall and in contact with said second anode coating for connecting said coating to a source of higher potential relative to that maintained on said first anode electrode during tube operation, said second anode coating including an area of high electrical resistance more adjacent said first anode electrode than said lead means for suppressing electrical discharges between said first and second anode electrode.

4. An electron discharge tube comprising an evacuated envelope, an electrode mounted within said envelope and adapted to be maintained at an operational potential, said electrode spaced from a portion of the wall of said envelope, a conductive coating on the inner surface of said wall portion, and conductive means for connecting said conductive coating to a source of higher potential relative to that maintained on said electrode during tube operation, said conductive means including a resistor of low electrical conductivity for suppressing an electrical discharge between said electrode and said conductive coating.

5. A cathode ray tube comprising an evacuated envelope, a first anode electrode mounted within said envelope and adapted to be maintained at an operational potential, said anode electrode spaced from the wall of said envelope, a second anode electrode including a conductive coating on the inner surface of said wall and conductive means for connecting said conductive coating to a source of high potential relative to that maintained on said first anode electrode during tube operation, said means including a resistor of low electrical conductivity for suppressing an electrical discharge between said first and said second anode electrodes.

6. A cathode ray tube comprising an envelope, a first anode electrode mounted within said envelope and adapted to be maintained at an operational potential, said anode electrode spaced from the wall of said envelope, a second anode electrode within said envelope comprising two portions insulatingly spaced from each other, one of said second anode portions arranged closer to said first anode electrode than the other of said anode portions, lead means for connecting said other anode portion to a source of higher potential relative to that maintained on said first anode electrode during tube operation, and a conductive means connecting said two second anode portions, said conductive means including a resistance element of low conductivity for suppressing an electrical discharge between said first and second anode electrodes.

7. A cathode ray tube comprising an evacuated envelope, a first electrode mounted within said envelope and adapted to be maintained at an operational potential, a second electrode spaced from said first electrode and having an adjacent part enclosing a portion of said first electrode, lead means connected to said second electrode remote from said first electrode for connecting said second electrode to a source of higher potential relative to that maintained on said first electrode during tube operation, said adjacent part enclosing a portion of said second electrode having high electrical resistance for suppressing electrical discharge between said first and second electrodes.

8. A cathode ray tube comprising an evacuated envelope, a first electrode mounted within said

envelope, said first electrode spaced from the wall of said envelope and adapted to be maintained at an operational potential, a second electrode including a conductive coating on the inner surface of said envelope wall, said coating having a portion enclosing part of said first electrode, lead means sealed through said envelope wall in contact with said conductive coating remote from said enclosing portion for connecting said second electrode to a source of higher potential relative to that maintained on said first electrode during tube operation, said enclosing portion of said second electrode having a high electrical resistance for suppressing electrical discharge between said first and second electrodes.

9. A cathode ray tube including an evacuated envelope, electrodes within said envelope for producing an electron beam, said electrodes comprising a first anode electrode spaced from the wall of said envelope and adapted to be maintained at an operational potential and a second anode electrode including a conductive coating on the inner surface of said envelope wall, a lead means sealed through said envelope wall in contact with one portion of said second anode coating for connecting said second anode to a source of higher potential relative to that maintained on said first electrode during tube operation, said conductive second anode coating including another portion enclosing at least part of said first anode electrode, said enclosing portion of a material having a high electrical resistance to suppress electrical discharge between said first and second anode electrodes.

10. A cathode ray tube including an evacuated envelope, electrodes within said envelope for producing an electron beam, said electrodes comprising a first anode electrode spaced from the wall of said envelope and adapted to be maintained at an operational potential and a second anode electrode including a conductive coating on the inner surface of said envelope wall, a lead means sealed through said envelope wall in contact with one portion of said second anode coating for connecting said second anode to a source of higher potential relative to that maintained on said first electrode during tube operation, said conductive second anode coating including another portion spaced on said inner envelope wall surface from said one portion, and a material of high electrical resistivity deposited on the inner envelope surface between said second anode portions and electrically connected to said anode portions for suppressing an electrical discharge between said first and second anode electrodes.

11. A cathode ray tube including an evacuated envelope, electrodes within said envelope for producing an electron beam, said electrodes comprising a first anode electrode spaced from the wall of said envelope and adapted to be maintained at an operational potential and a second

anode electrode including a conductive coating on the inner surface of said envelope wall, a lead means sealed through said envelope wall in contact with one portion of said second anode coating for connecting said second anode to a source of higher potential relative to that maintained on said first electrode during tube operation, said conductive second anode coating including another portion spaced on said inner envelope wall surface from said one portion, a resistance element of low conductivity, and means connecting said resistance element between said second anode portions for suppressing an electrical discharge between said first and second anode electrodes.

15 12. A cathode ray tube comprising an evacuated envelope, a first anode electrode, mounted within said envelope and adapted to be maintained at an operational potential, said first anode electrode spaced from the wall of said envelope, a second anode electrode including a conductive coating on the inner surface of said wall, lead means connected to one portion of said second anode coating for connecting said anode to a source of higher potential relative to that maintained on said first anode electrode during tube operation, and means of high electrical resistivity electrically connected to said second anode coating in the electrical path between said first anode electrode and said lead means.

20 13. A cathode ray tube comprising an evacuated envelope, a first electrode mounted within said envelope and adapted to be maintained at an operational potential, said first electrode spaced from the wall of said envelope, a second electrode including a conductive coating on the inner surface of said wall, lead means connected to one portion of said second electrode coating for connecting said second electrode to a source of higher potential relative to that maintained on said first anode electrode during tube operation, and means of high electrical resistivity connected to said second electrode coating in the electrical path between said first electrode and said lead means.
